UNITED STATES PATENT OFFICE

162,303

COMBINATION GRINDING AND SURFACING TOOL

Arthur O. Hughes, Anglesey, North Wales

Application September 8, 1950, Serial No. 12,110

Term of patent 14 years

(Cl. D37—1)

To all whom it may concern:

Be it known that I, Arthur Owen Hughes, subject of the King of Great Britain and Ireland, residing at Anglesey, North Wales, have invented a new, original, and ornamental Design for a Combination Grinding and Surfacing Tool, of which the following is a specification, reference being had to the accompanying drawing, forming part thereof.

Figure 1 is a front perspective view of the combination grinding and surfacing tool, showing my new design; and

Figure 2 is a rear perspective view thereof.

I claim:

The ornamental design for a combination grinding and surfacing tool, as shown.

ARTHUR O. HUGHES.
